UNITED STATES PATENT OFFICE

2,312,166

DWELLING

Llewelyn Hughes, Pasadena, Calif.

Application December 24, 1941, Serial No. 424,347

1 Claim. (Cl. 20—1.1)

This invention relates to the official class of buildings and more particularly a dwelling or other type of building to be occupied by individuals.

The primary object of this invention resides in constructing a dwelling or the like so as to permit individuals therein to look out toward the front thereof from three sides of the same.

Another object of this invention resides in constructing a dwelling or the like so as to permit individuals in the back rooms thereof to look out toward the back and sides of the same.

A further object of this invention resides in constructing a dwelling or the like so as to permit a wide view of the territory surrounding the same.

With these and other objects in view this invention resides in certain novel features of construction and arrangement of elements to be hereinafter more particularly set forth in the specification, illustrated in the accompanying drawings and pointed out in the appended claim and, while this disclosure depicts my present conception of the invention, the right is reserved to resort to such changes in construction and arrangement of elements as fall within the spirit of the invention.

In the accompanying drawings forming a part of this application;

Fig. 1 is a view of a building plot showing a dwelling in plan thereon as constructed in accordance with this invention.

Fig. 2 is a side view thereof.

Fig. 3 is a horizontal sectional view thereof approximately on line 3—3 of Fig. 2 showing one form of floor plan.

Fig. 4 is a similar view of the opposite side thereof.

Fig. 5 is a front view thereof.

Fig. 6 is a rear view thereof.

In the present illustration of this invention the numeral 5 designates, in general, a dwelling constructed in accordance with this invention, the same being herein shown as disposed on a building plot B in front of which is a roadway or street R leading from which is a drive way D having a path P leading therefrom to the entrance side of the dwelling and, while the dwelling is so disposed on the building plot in the instant case, it may be otherwise arranged thereon without destroying the salient features of the invention.

The dwelling 5 consists of a floor 8, front, side and rear walls 9, 10 and 11 over which is dis-

posed a roof 12, the same being constructed to form a substantially compound triangle in plan consisting of a front triangular portion 13 and rear triangular portion 14 having their base lines coinciding, said front triangular portion is preferably of greater area than the rear triangular portion and, while herein shown as having a substantially semi-circular front wall, the same may be of any approved configuration.

5 10 The side walls 10 are of uniform height and merge into the rear walls which increase in height towards a perpendicular line at the apex thereof and, through the instrumentality of walls so formed, the roof disposed thereon slants forwardly with those areas on opposite sides of the longitudinal ridge line thereof slanting toward opposite sides of the dwelling, it being understood that the edges of the roof may be flush with the walls or project thereover.

15 20 Disposed in the walls are a suitable number of windows W and doors O and, while the same are herein arranged more particularly to clearly set forth the salient features of the invention, it is within the purview of this invention to rearrange 25 the same and use any type of window and door as will permit practice of the invention in a like manner.

20 30 Although a definite floor plan is herein shown in Fig. 3 it is to be understood rearrangement thereof is optional with the builder in meeting the demands of the public.

35 35 Fireplaces, chimneys, plumbing and other standard conveniences (not shown) may be built into the dwelling as the builder elects.

With this invention fully set forth it is manifest that a novel form of dwelling is provided and, through arrangement of the windows, individuals within have a wide range of vision from the interior of the dwelling.

40 45 Having thus described my invention what I claim and desire to protect by Letters Patent is:

A building of substantially diamond shape in plan with its front portion being of greater area than its rear portion, a ridge beam extending longitudinally of the roof of the building and directed downwardly from the medial point of a lateral line passing through the widest portion of the roof and its ends terminating at the front and rear extremities of the building, and a substantially semi-circular transparent wall at the front end of the larger portion of the building.

LLEWELYN HUGHES.
